UNITED STATES PATENT OFFICE

2,089,291

HUMIDIFYING RADIATOR

Enoch E. Neal, Malden, Mass.

Application May 20, 1935, Serial No. 22,311

4 Claims. (Cl. 237—78)

This invention relates to improvements in humidifying radiators.

The object of the invention is to provide a radiator of the character mentioned having a plurality of groups of radiator sections embodied therein between which humidifiers similar in shape to the radiator sections are interposed, said humidifiers being loosely mounted upon the coupling means for the radiator sections and being removable therefrom without disturbing either the radiator sections or their coupling means.

Another object of the invention is to provide a novel control means whereby the heating fluid for the radiator may be admitted to the several groups of radiator sections, said control means permitting condensation within the radiator sections to drain therefrom automatically when the control means is located in a closed position and when the pressure of the heating fluid is relieved.

Still another object of the invention is to so position the humidifier with respect to a group of radiator sections and an air valve therefor that the air valve will be confined within the humidifier and discharge thereinto.

The invention consists in a radiator as set forth in the following specification and particularly as pointed out in the claims thereof.

Referring to the drawing:

Fig. 1 represents a front elevation of a humidifying radiator embodying my invention, certain portions of said radiator being broken away and illustrated in section.

Fig. 2 is a vertical sectional elevation taken on the line 2—2 of Fig. 1, looking in the direction of the arrows on said line.

Fig. 3 is an enlarged vertical longitudinal sectional view of the valve which controls the admission of heating fluid into the radiator and permits condensation to drain outwardly therethrough.

Fig. 4 is a detail view illustrating a portion of the valve mechanism as viewed in the direction of the arrow Fig. 3.

Fig. 5 is an enlarged detail vertical section through a portion of the valve as taken on the line 5—5 of Fig. 2.

Like numerals refer to like parts throughout the several views of the drawing.

In the drawing, A represents a radiator embodying therein a plurality of groups B, C and D 50 of radiator sections 6 of any desired construction and well known in the art. There may be any number of groups of sections desired and each group may consist of any number of sections 6 desired. The sections 6 of each group of sections 55 may be connected together at the top and bottom

thereof in any well-known manner. The groups of sections are connected one to another adjacent to the top thereof and also spaced apart a distance equal to the width of a radiator section. 6 by means of suitable coupling members 7 which 5 are closed at one end thereof at 8 to prevent the heating fluid from passing from one group of sections to another at the top of the radiator. At the bottom of the radiator the groups of sections are connected together and also spaced the re- 10 quired distance apart by means of valves 9.

The valves 9 are of novel construction and constitute manually controlled gravity and pressure actuated means for controlling the passage of the heating fluid from one group of radiator sections to another, and said valves also permit condensation in the groups of sections to drain therefrom automatically when the pressure of the heating fluid is relieved. Each valve 9 embodies therein a casing 10 having a chamber 11 therein in which a valve member 12 is mounted to contact with an inclined valve seat 13. The valve member 12 is loosely mounted on a pin 14 which projects into an end of a valve rod 15 and in effect constitutes a part of said valve rod, and said pin and rod are mounted to rock in unison in bearing portions 16 and 17 forming a part of the casing 10. The valve rod 15 has a projection 18 formed thereon which projects into a recessed portion 19 of the valve member 12, said recess being slightly 20 wider than the projection 18, thereby permitting a slight amount of lost motion between said members. A handle 20 is provided for the valve rod 15, said handle preferably being heavier upon one side of said rod than upon the other to overbalance the weight of the valve member 12 when the latter is located in its open position if the rod becomes loose in its stuffing box.

The valve member 12 is raised from the seat 13 to an open position by rotating the valve rod 15 in a counterclockwise direction as viewed from the front of the radiator, while the movement of said rod in a clockwise direction will permit the valve member 12 to drop by gravity from its raised or open position to its closed position against the seat 13, and when said valve member is located in this position steam pressure in the chamber 11 will hold the valve member still more tightly closed. When the steam pressure in the chamber 11 is relieved any pressure upon the opposite side of the valve member 12, such as may be caused by condensation accumulating in the radiator sections 6 and rising to a level therein where it will enter a passage 21 of the valve, will cause the valve member to open slightly because of the move- 40 45 50 55 60 65 70 75 80 85 90 95

ment permitted by a space 22 between the lower edge of the projection 18 and the lower edge of the recess 19, thereby permitting said condensation to drain through the valve. A reducing bushing 23 has screw-threaded engagement with the valve casing 10 and has a passage 24 extending therethrough which communicates with the valve chamber 11 and adjacent radiator section 6. The rotary movement of the valve rod 15 in the casing 10 is limited by a stop screw 25 which projects from said casing into a groove 26 provided in said rod.

A valve 27 for controlling the admission of steam into the group D of radiator sections is constructed and operates in the same manner as are the valves 9, except that the casing thereof is formed as an elbow.

Located between each group of radiator sections 6 above the valves 9 is a humidifier 28 embodying 20 therein a receptacle 29 for water and a cover 30 therefor. The receptacle 29 is removably supported at 31 upon the coupling member 7 and is prevented from swinging or moving at the bottom thereof by reason of the fact that a recessed portion 32 of the receptacle engages a top portion of the valve 9. The humidifier 28 is constructed to resemble the form and appearance of the radiator sections 6 and present a pleasing appearance between said sections, and the heat transmitted 30 by radiation from the sections 6 will effectively heat the water located in the receptacle 29. Openings 33 are provided in the sides of the cover 30.

Air valves 34 well known in the art are provided for each group of radiator sections being attached 35 to the coupling members 7 and if there is any leakage of moisture from said valves it will drip into the receptacle 29 of the humidifier, and any noise of steam or air escaping from the radiator through the valves 34 is effectively muffled. A 40 flange 35 projects downwardly from the bottom of the receptacle 29 in front of the valve 9 and effectively obscures a large part of said valve from view.

It will be evident that any number of groups of 45 radiator sections 6 may be utilized as may be required to provide the amount of heat desired. If all of the humidifiers 28 are not required, the water may be eliminated therefrom as desired. These humidifiers may be easily and quickly 50 moved from between the groups of radiator sections whenever it is found necessary to remove the water therefrom or clean the receptacle 29 without disturbing the radiator sections or their coupling means. Condensation within the radiator 55 sections will drain therefrom automatically when-

ever the steam pressure within the radiator is relieved.

I claim:

1. A radiator comprising groups of radiator sections communicating one with another at the bottom thereof, a coupling connecting adjacent groups of radiator sections together at the top thereof and preventing a heating fluid from passing therebetween, and a humidifier simulating the radiator sections and interposed between groups of radiator sections and loosely suspended upon said coupling, whereby said humidifier may be removed from between the groups of sections without loosening the radiator sections and their coupling means. 15

2. A radiator comprising groups of radiator sections, a coupling connecting adjacent groups of radiator sections together at the top thereof and preventing a heating fluid from passing therebetween, a valve connecting adjacent groups of 20 radiator sections at the bottom thereof, and a humidifier interposed between groups of radiator sections and loosely suspended upon said coupling, whereby said humidifier may be removed from between the groups of sections without loosening the coupling means, said humidifier being positioned at the bottom thereof by having engagement with said valve. 25

3. A radiator comprising groups of radiator sections communicating one with another at the bottom thereof, a coupling connecting adjacent groups of radiator sections together at the top thereof and preventing a heating fluid from passing therebetween, a humidifier interposed between groups of radiator sections and loosely suspended upon said coupling, whereby said humidifier may be removed from between the groups of sections without loosening the radiator sections and their coupling means, and an air valve for a 35 group of radiator sections, said valve being attached to the coupling and communicating with the radiator sections therethrough and being confined within and discharging into said humidifier. 40

4. A radiator comprising groups of radiator sections communicating one with another at the bottom thereof, a closed nipple connecting adjacent groups of radiator sections together at the top thereof and preventing communication therebetween, and a humidifier simulating the radiator sections and interposed between groups of said 50 sections and loosely suspended upon said nipple, whereby said humidifier may be removed from between the groups of sections without loosening the radiator structure. 45
